[57] CLAIM

The ornamental design of an eyeglass frame attachable/detachable glass guard, as shown and described.

DESCRIPTION

FIG. 1 is a perspective view of an eyeglass frame attachable/detachable glass guard showing my new design attached to the upper section of an eyeglass frame; FIG. 2 is a top plan view of the guard detached from the eyeglass frame;

FIG. 3 is a bottom plan view of the guard detached from the eyeglass frame;

FIG. 4 is a front elevational view of the guard detached from the eyeglass frame;

FIG. 5 is a back elevational view of the guard detached from the eyeglass frame; and,

FIG. 6 is a right side elevational view of a guard detached from the eyeglass frame, the left side elevational view being a mirror image thereof.
